(No Model.)

C. H. COX.

SAND BOX FOR ELECTRIC OR OTHER CARS.

No. 556,712.

Patented Mar. 17, 1896.

UNITED STATES PATENT OFFICE.

CHARLES H. COX, OF HAVERHILL, MASSACHUSETTS, ASSIGNOR OF ONE-HALF TO S. PORTER GARDNER, OF SAME PLACE.

SAND-BOX FOR ELECTRIC OR OTHER CARS.

SPECIFICATION forming part of Letters Patent No. 556,712, dated March 17, 1896.

Application filed December 17, 1895. Serial No. 572,472. (No model.)

To all whom it may concern:

Be it known that I, CHARLES H. COX, a citizen of the United States, residing at Haverhill, in the county of Essex and State of Massachusetts, have invented a new and useful Improvement in Sand-Boxes for Electric or other Cars, of which the following is a full, clear, and exact description, reference being had to the accompanying drawings, forming a part of this specification, in explaining its nature.

The invention relates to a sand-box adapted to be carried or supported in front of the dasher of the car, and to be easily detachable or removable therefrom, and which is provided with means for releasing the sand therefrom into a chute for agitating or breaking it up, and permitting the end of the chute to be moved from the position which it occupies when the car is upon a straight track to that which it must occupy to deliver sand upon the track when the car is upon a curve.

In the drawings, Figure 1 is a view in front elevation of the portion of the front of a car, representing a part of a dasher and the sand-box attached thereto. Fig. 2 is a view in side elevation of a portion of the front end of a car, showing the sand-box attached to the dasher, the casing of the sand-box being broken out near the top to show the agitator. Fig. 3 is a view in plan, showing a portion of the dasher and the top of the sand-box. Fig. 4 is a view in side elevation, enlarged, of the sand-box, a portion of the casing thereof near the top and bottom being removed. Fig. 5 is a view in horizontal section upon the dotted line 5 5 of Fig. 4 and in plan of parts below the same; and Fig. 6 is also a view in horizontal section upon dotted lines 6 6 of Fig. 4, and plan to represent one outlet and its closing-valve.

A represents the dasher of an electric or other car; a, its top rail.

B is the sand-box. It is provided upon its back side at the top with hooks b b, which hook upon the rail a, forming means by which the sand-box is suspended from the rail and attached to the car, and by which it may be easily removable. The box also has the buffers b' at the upper end, which are parts of the hooks, and b'' at its lower end, which serve

to hold the box slightly removed from the front of the dasher, so that it shall not wear the paint from the dasher, and also more especially to provide room for the lever C, to 55 which reference will be hereinafter made. The box is preferably made with a wooden back, metal sides b⁴ and front b⁵ in one piece, and a wooden or metal bottom b⁶ and top b⁷. The top has a hole b⁸ through which the sand 60 is introduced, and which is closed by a cover b⁹. The bottom has the outlets b¹⁰, which open into the upper part or section d of the chute D. I prefer that there be two outlets, and each may extend upon both sides of the shafts 65 e e', as represented in Fig. 6. They are adapted to be closed by the valves E E', (see Figs. 4, 5 and 6,) the valves being mounted respectively upon the shafts e e'. These shafts extend upward through the box and have bearings in 70 the top and bottom thereof, and one of them, the shaft e, extends through the top and carries above the top the horizontal operating-lever E², by which the shafts are partially turned, the shaft e being connected with the 75 shaft e' by the arms e² extending from each, and a connecting-link e³. (See Fig. 5.)

Upon the movement of the lever E² in one direction, the outlets are opened and sand is permitted to escape from both outlets, and 80 upon the movement of the lever in the reverse direction the outlets are closed, the valves being moved over them. The shafts e e' also carry arms or blades e⁴, (see Figs. 2, 4, and 5,) and these blades or arms being moved in the 85 sand as the shafts are moved to uncover and cover the outlets break it up or disintegrate it or keep it in a loose condition, so that it will always feed freely through the outlets, and this is of value, as it permits sand of any 90 consistency or condition to be employed—that is, it is not necessary that the sand be dried before use. The chute D is made in three sections. The upper part d preferably has the straight side d¹ and the inclined side 95 d², which brings its lower end d³ to a position over or very nearly over a rail. To the lower end of this section d there is attached the section d⁴ by means of pivots d⁵, which extend through ears on the upper part of the section 100 d⁴ into the lower section d¹, the upper end of the section d⁴ being somewhat enlarged to re-

ceive and lap upon the lower end d^3 of the section d' . This provides the lower end d^6 of the section d^4 with a lateral movement, by which its location may be varied at the will 5 of the motorman or car-driver through the instrumentality of the lever C, before referred to, and which extends between the back of the sand-box and the front of the dasher to a point above the rail, and which is pivoted at c to the back of the sand-box and is connected with the section d^4 by the arm c' , (see Figs. 1 and 2,) which is rigidly united to the said section, extends upwardly therefrom, and is connected with the lower end to 10 the lever C by the link c^2 . (See Figs. 1 and 2.) By moving the upper end of the lever the end d^6 of the chute-section d^4 is moved laterally to bring it over the track when upon a curve. It will be understood that this movement is 15 only necessary in feeding sand to a curved track. As ordinarily set it would not deliver sand to a curved track unless it were so moved, as its lower end would then be out of line with the curve; but by means of the lever the 20 end can be moved quickly to its new position and held there while upon the curve and then returned again to its normal position. There is attached to this lower movable end d^6 of the chute a section d^7 , which is open at d^8 , is 25 pivoted at d^{10} , and which is inclined in relation to the section d^4 , and acts to receive the sand from said section and to break the force of its fall and direct it in a compact stream upon the rail. It is shaped very much like 30 a scoop, and it is held in place by friction, so that its angle may be somewhat changed and it can be folded upwardly against or upon section d^4 when not in use.

The sand-box is placed preferably upon the 35 motorman's left, and its operating-levers—namely, the lever E^2 and the lever C—are thus brought in close relation with the lever of the electric controller.

In use the movement of the lever E^2 in one 40 direction moves the valves from over the outlets E and permits sand to escape, and its movement in the reverse direction closes said outlets. The same movement operates both valves and also the agitator or fingers e^4 , 45 therefore at the same time breaking up and agitating the sand. Upon the movement of the lever C the position of the lower end of the chute is caused to be changed to any desired extent for the purposes above named.

It will be seen that all the parts of the box, 50 including its operating devices, are connected together and are detachable together from the car, and that they are thus easily removed from one car to another or from one end of 55 the car to the other. It will also be noticed that the box is located where it can be easily filled and takes no valuable car-space; also, that it can be readily detached at any time and need not be applied to the car, excepting 60 in wet or slippery weather. I prefer that the fingers, blades, or agitators be arranged spirally upon the shafts.

Having thus fully described my invention, I claim and desire to secure by Letters Patent of the United States—

1. A sand-box having an outlet and means for closing it, the section d extending from the sand-box and open at its lower end, and the movable section d^4 of the chute pivoted at its upper end to the section d and means for moving it laterally, substantially as described. 75
2. A sand-box having an outlet, and means for closing it, a movable member d^4 of a chute and means for operating it and an inclined end d^7 , substantially as described. 80
3. A sand-box having a chute and an open end d^7 attached to the chute in a manner to permit its angle to be varied, substantially as described. 85
4. A sand-box having a chute and an end d^7 open upon its top and connected with the chute in a manner to permit it to be turned upward against the same, substantially as described. 90
5. A sand-box having the movable chute-section d^4 and means for moving the same, comprising the arm c' and lever C pivoted to the back of the sand-box and connected with the arm c' by the link c^2 , substantially as described. 95
6. A sand-box having the buffers b' , b^2 , and the movable chute-section, and the lever C, connected at its lower end with the movable chute-section and pivoted to the back of the box inside the outer surface of the buffers, as and for the purposes described. 100
7. A sand-box having the two outlets b^{10} , their respective valves, E, E' , the shafts e , e' , the shaft e' being connected with the shaft e , 105 and being operated therefrom, and means for turning forward and backward shaft e .
8. A sand-box having the outlets b^{10} in its bottom, the valves E, E' therefor, shafts e , e' , shaft e' being connected to shaft e to be operated thereby, the agitators e^4 carried by said shafts, and means for operating shaft e . 110
9. A sand-box having the outlets b^{10} and the valves E, E' , and means for simultaneously operating them, and the section d of the sand-chute, into which both outlets b^{10} open. 115 as and for the purposes described.
10. A detachable sand-box having in its bottom an outlet, and means for opening and closing the same, an agitator for breaking up and loosening the sand in the box, a chute-section below the bottom of the box, formed with the straight sides d' and the inclined sides d^2 , the laterally-movable chute-section d^4 pivoted to the lower end of the section d' , and means for moving it laterally and the end d^7 pivoted to the lower end of the section d^4 . 120 and adapted to extend backwardly therefrom, as and for the purposes specified. 125

CHARLES H. COX.

In presence of—
M. A. PINGREE,
GEORGE H. W. HAYES.
